US00D682073S

(12) United States Design Patent
Payne

(10) Patent No.: US D682,073 S
(45) Date of Patent: * May 14, 2013

(54) STRAP REEL TOOL

(76) Inventor: Jack Payne, Chandler, IN (US)

() Term: 14 Years

(21) Appl. No.: 29/419,077

(22) Filed: Apr. 25, 2012

(51) LOC (9) Cl. 08-05

(52) U.S. Cl.

USPC D8/359

(58) Field of Classification Search D8/14,
D8/51, 44, 70, 356, 358-359; 242/390, 395;
254/243, 323

See application file for complete search history.
